(57) **CLAIM**

The ornamental design for a medication alert unit, as shown and described.

DESCRIPTION

FIG. 1 is a perspective view showing the front, right side and top of a medication alert unit generally in the shape of a cat's paw and pad in addition to a push button and a light.

FIG. 2 is a top view of a medication alert unit generally in the shape of a cat's paw.

FIG. 3 is a front view of a medication alert unit generally in the shape of a cat's paw.

FIG. 4 is a right side view of a medication alert unit generally in the shape of a cat's paw. The left side view is a mirror image; and,

FIG. 5 is a bottom view of a medication alert unit generally in the shape of a cat's paw.
